CASING FOR MECHANICAL FUSE MECHANISMS

André Varaud, Geneva, Switzerland

Application May 31, 1934, Serial No. 728,432
In Switzerland June 7, 1933

7 Claims. (Cl. 102—36)

The invention relates to a casing for mechanical fuse mechanism. This casing is composed of a cylinder in one piece, of which the end intended to contain the movable frame of the mechanism has axial slots intended to give a certain elasticity to this end of the wall of the casing, with a view to producing a frictional grip on the said mobile frame.

The annexed drawing represents an example of construction of a casing according to the invention, and also shows a section of a casing of the usual type.

Fig. 1 is a section of the usual type of casing,

Fig. 2 is a view in elevation of a form of construction of the improved casing of this invention, of which:

Fig. 3 is a vertical section on line III—III of Fig. 4.

Fig. 4 is a plan view of Fig. 3.

Fig. 5 is a section on line V—V of Figs. 2 and 3.

Casings for the purpose described hitherto used are in two parts forming two half-cylinders 1 and 2, as shown in section in Fig. 1.

As is known, in certain types of mechanical fuse, as shown for example in U. S. Patent No. 1,665,899, the mechanism comprises two frames, one of which is fixed and carries the motor members and the driving gear of the fuse hammer, and the other is movable and carries the regulator members.

In the mounting of casings of the type shown in Fig. 1, the two parts 1 and 2 of the casing are screwed by means of screws passing through orifices 3, on the fixed frame of the mechanism, the movable frame being simply held by pressure between the halves of the casing and the centering of the members being effected with a certain difficulty at the tightening of the above mentioned screws.

For the purpose of eliminating this centering difficulty, the casing according to the invention is formed of a one piece, cylinder 4 illustrated in Figs. 2 to 5.

The cylinder is provided with orifices 5 for the passage of screws intended to immobilize the fixed frame of the fuse mechanism and is also provided with axial slots 6, four in number in the example shown, these slots starting from the end of the casing in which the movable part contains the regulator members of the mechanism.

The fixed frame and the casing are of such dimensions that the former fits exactly in the latter, while the movable frame and the part of the casing for its accommodation are of such di-

mensions that the said movable frame can only be inserted in the casing through a certain effort necessitating a slight yielding of the walls of the latter, allowed for by the slots 6 which give a certain elasticity to this part of the casing.

Inside the casing flanges or ribs such as 7, 8 can be provided and a machined part such as 9 operating as a support for the correct placing in position of both frames of the mechanism, the flanges 1 and 8 serving, in particular, as distance stops between the two frames.

Finally, the lateral orifices of the casing, needed for the regulation of the regulator members, can either be formed in the solid portions of the wall of said casing, or, as shown at 10 and 11, be formed across a slot 6.

It is obvious that the number of slots can vary and need not necessarily be the number represented.

What I claim as my invention and desire to secure by Letters Patent of the United States is:—

1. In a mechanical fuse mechanism for projectiles having a fixed frame and a movable frame, a casing for said frames comprising a one-piece hollow cylindrical member adapted to receive the movable frame in one end thereof and the fixed frame in the other end, the cylindrical wall of the end of the casing adapted to receive the movable frame being provided with an axially extending slot to impart elasticity thereto and to frictionally retain the movable frame in said casing.

2. In a mechanical fuse mechanism for projectiles having a fixed frame and a movable frame, a casing for said frames comprising a one-piece hollow cylindrical member adapted to receive the movable frame in one end thereof and the fixed frame in the other end, the cylindrical wall of the end of the casing adapted to receive the movable frame being provided with an axially extending slot to impart elasticity thereto and to frictionally retain the movable frame in said casing, and means carried by the interior of said casing for supporting the frames therein.

3. In a mechanical fuse mechanism for projectiles having a fixed frame and a movable frame, a casing for said frames comprising a one-piece hollow cylindrical member adapted to receive the movable frame in one end thereof and the fixed frame in the other end, the cylindrical wall of the end of the casing adapted to receive the movable frame being provided with an axially extending slot to impart elasticity thereto and to frictionally retain the movable frame in

said casing, means carried by the interior of said casing for supporting the frames therein, and a portion of the interior of said casing being machined to provide a support for said frames.

4. In a mechanical fuse mechanism for projectiles having a fixed frame and a movable frame, a casing for said frames comprising a one-piece hollow cylindrical member adapted to receive the movable frame in one end thereof and the fixed frame in the other end, the cylindrical wall of the end of the casing adapted to receive the movable frame being provided with an axially extending slot to impart elasticity thereto and to frictionally retain the movable frame in said casing, said casing having a lateral orifice formed in the slotted wall thereof across a slot to provide access to the movable frame.

5. In a mechanical fuse mechanism for projectiles having a fixed frame and a movable frame, a casing for said frames comprising a one-piece hollow cylindrical member adapted to receive the movable frame in one end thereof and the fixed frame in the other end, the cylindrical wall of the end of the casing adapted to receive the movable frame being provided with an axially extending slot to impart elasticity thereto and to frictionally retain the movable frame in said

casing, and annular ribs on the interior of said casing for supporting the frames therein.

6. In a mechanical fuse mechanism for projectiles having a fixed frame and a movable frame, a casing for said frames comprising a one-piece hollow cylindrical member adapted to receive the movable frame in one end thereof and the fixed frame in the other end, the cylindrical wall of the end of the casing adapted to receive the movable frame being provided with an axially extending slot to impart elasticity thereto and to frictionally retain the movable frame in said casing, and annular ribs on the interior of said casing for supporting the frames therein, said casing having a lateral orifice formed in the slotted wall thereof across a slot to provide access to the movable frame.

7. In a mechanical fuse mechanism for projectiles having a movable frame, a casing for said frame comprising a one-piece hollow cylindrical member adapted to receive the movable frame in one end thereof, the cylindrical wall of the end of the casing adapted to receive the movable frame being provided with an axially extending slot to impart elasticity thereto and to frictionally retain the movable frame in said casing.

ANDRÉ VARAUD.
